UNITED STATES PATENT OFFICE.

JOSEF HENRIK HALLBERG, OF NEW YORK, N. Y., ASSIGNOR TO GENERAL INCANDESCENT ARC LIGHT COMPANY, OF SAME PLACE.

ELECTRIC-ARC LAMP.

SPECIFICATION forming part of Letters Patent No. 678,560, dated July 16, 1901.

Application filed November 13, 1900. Serial No. 36,322. (No model.)

To all whom it may concern:

Be it known that I, JOSEF HENRIK HALLBERG, a citizen of the United States, residing at New York city, county and State of New 5 York, have invented certain new and useful Improvements in Electric-Arc Lamps, of which the following is a specification.

My invention relates to electric-arc lamps of the type known as "inclosed-arc lamps;" 10 and it consists in various details of construction, which will be described in the specification and specified in the claims.

The object of my invention is to simplify and improve the construction of such lamps 15 and decrease their cost.

The accompanying drawings will serve to illustrate my invention, and in which similar letters of reference indicate like parts.

Figure 1 is a vertical section with a portion 20 of the parts shown in elevation. Fig. 2 is a side view. Fig. 3 is a vertical section through the supporting-tube which incloses the upper carbon, dash-pot, and arm which connects the dash-pot to the magnet-armatures and shows 25 the relation of these parts.

In the drawings, A indicates the top plate or cover of the lamp. Depending from this cover is a supporting-tube B. Secured to the tube B about midway is an annular plate C, 30 which forms a support for the series magnets D and shunt-magnets D'. Located within the magnets are the armatures E. The armatures are connected together at the top through the plate E', which surrounds the tube B, and is connected through the arm F with the dash-pot G. The dash-pot G is situated over the piston G', which is secured to the sleeve H, fixed on the tube B. The lower ends of the armatures are connected together 35 through the plate I, which also surrounds the tube B. Depending from this plate are the pivoted clutch-arms J, connected together through the spring J'.

Located within the supporting-tube B is the 40 upper carbon K. The carbon K is carried in the carbon-holder K', which is connected through the conducting-cord L with a source of electric energy.

The magnets D and D' are the well-known 45 differential magnets, and the movement of

the upper carbon will be fully understood without further description.

Mounted on the lower end of the tube B is an annular plate M, to which is secured a larger annular bottom plate M'. These plates 55 are separated by an air-space and buttons of insulating material M², Fig. 1. The annular opening in the plates M and M' is sufficient to allow free vertical and lateral movement of the clutch-arms J.

Depending from the tube B is a bracket N, upon the lower end of which is mounted an annular hollow casting O, within which is located and supported a gas-cap P. Surrounding the casting O is a reflector Q. The 65 casting O is larger in diameter than the gas-cap P, thereby permitting free vertical and lateral movement of the gas-cap within it. The casting O is provided with a pair of lateral arms R, perforated vertically and with 70 in which are located insulating-tubes S. Situated within the insulating-tubes are sleeves T, provided with shoulders above and below the insulating-tubes, by reason of which the sleeves T are held in position on the lateral 75 arms R.

U represents the frame which supports the lower carbon K². The frame U has side arms U', which are carried upward through the sleeves T. These arms are jointed at V, so 80 that the lower portion of the frame U can be swung at an angle, as shown in Fig. 2.

Located between the upper shoulders on the sleeves T and washers on the ends of the arms U' are the springs W. The bottom of 85 the frame U has formed in it an opening X, adapted to receive the arm Y, projecting from the bottom of the support Y' of the arc-inclosing globe Z.

The operation of that part of the lamp 90 mechanism which supports the lower carbon and the arc-inclosing globe will be readily understood. The springs W exert an upward pressure upon the arms U' and draw the frame U upward and the jointed portion 95 of the arms within the cavity of the sleeves T, at the same time pressing the top of the arc-inclosing globe into firm contact with the bottom of the gas-cap.

When it is desired to remove the arc-inclos- 100

ing globe to introduce a new lower carbon, the frame U is pulled downward, thus compressing the springs W until the jointed portion of the arms U' is below the cavity of the sleeves T. The frame is then swung to the right or the left, when the globe Z can be removed.

Having thus described my invention, I claim—

- 10 1. In an arc-lamp, in combination with a supporting-tube, a casting secured to the tube and having lateral perforated arms, a frame for supporting the lower carbon, provided with jointed side arms, and resilient means for normally holding the jointed portions of the frame within the cavity of the arms of the casting.
- 15 2. In an arc-lamp, in combination with a supporting-tube, an annular plate secured to the tube, pairs of magnets having their armatures in line and adapted for simultaneous movement, a plate connecting the armatures at the top, a dash-pot connected to the plate, a plate connecting the armatures at the bot-

tom, and a clutch mechanism connected to 25 the last-named plate.

3. In an arc-lamp, in combination with the bottom plate of that portion of the lamp carrying the actuating mechanism, a bracket depending therefrom, carrying a hollow casting 30 provided with lateral arms, a gas-cap mounted in the casting, an arc-inclosing globe, a frame for supporting the arc-inclosing globe, provided with jointed side arms adapted for vertical movement in the arms of the casting, and means for exerting a constant upward pressure upon the supporting-frame, whereby the jointed side arms of the frame are brought within the cavity of the arms of the casting and the frame locked in position, 40 and the top of the arc-inclosing globe into contact with bottom of gas-cap.

In testimony whereof I affix my signature in the presence of two witnesses.

JOSEF HENRIK HALLBERG.
